George W. McElhone, Inventor

UNITED STATES PATENT OFFICE.

GEORGE W. MCELHIONE, OF BINGHAMTON, NEW YORK, ASSIGNOR OF ONE-HALF TO WELINGTON D. SMITH, OF SAME PLACE.

PRINTING-PRESS.

SPECIFICATION forming part of Letters Patent No. 414,869, dated November 12, 1889.

Application filed June 29, 1889. Serial No. 316,079. (No model.)

To all whom it may concern:

Be it known that I, GEORGE W. MCELHIONE, a citizen of the United States, residing at Binghamton, in the county of Broome and State 5 of New York, have invented certain new and useful Improvements in Printing - Presses; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 Similar letters refer to similar parts throughout the several views.

My invention is an improvement in printing-presses for printing upon thick stiff sheets, and is designed more especially for printing 20 upon cigar-boxes, the printing being done after the box is cut and before it is nailed up.

The invention consists in the arrangement and combination of the several devices, by which the boards are fed regularly to the 25 press, a uniform impression is secured, and the press is made substantially automatic in its operation.

In the accompanying drawings, Figure 1 is a perspective of my improved press, the end 30 of the frame and also the end of the pitman being broken off, as they contain nothing new, the same driving mechanism being employed as in the ordinary presses. Fig. 2 is a longitudinal vertical section showing the 35 construction of the bed-plate B and also the position of the several parts when the board is passing under the pressure-roller, where it receives the impression. Fig. 3 is a cross-section of one of the fingers f which drive 40 the board through. Fig. 4 is a detail of a part of one side of the press, showing the 45 gage for holding the different widths of boards, with its means of adjustment. Fig. 5 is a vertical cross - section cut on two different 50 lines, the right-hand side being cut through the head or face-plate of the bed, and the left-hand side being cut through the type-bed. Fig. 5 also contains a detail of the lower end of the rod i, which holds the ink-roller 55 down to place.

The frame A is cast, preferably, in a single

piece, though any of the ordinary forms of frame may be used. At the upper inside it is fitted with a slideway for the bed-plate B to travel in, as shown most clearly in the 55 cross-section at Fig. 5. Over this slideway are the plates a a to hold the bed down to place, and these run forward to the gage-plates G, a little forward of the ink-roller I, and are bolted down upon the frame. Between these plates a a and the pressure-roller R are the gage-plates G, of which one is shown clearly in Fig. 4, which also cover the slideway, and are held down upon the frame by bolts passing through slots in the 60 plates to admit of their being moved to a greater or less width apart. But one of these plates is shown in the drawings, the opposite one being hidden by the upright g', which it carries. These are moved out 65 or in, according to the width of boards to be printed, which are piled in flatwise between them, and are held by the uprights attached to and moving with them. The upright attached to the front gage is shown in outline 70 in Fig. 4 and in dotted lines in Fig. 1. Across the machine and fastened to the frame is another upright g', which must be set just far enough above the slotted springs H H to allow a single board to be driven through under it. Attached to the block which carries the pressure-roller is the slotted adjustable arm e, which runs outside and around the front upright and across the machine to hold the boards from that direction, and may be 75 moved back and forth on the bolts to fit it to the length of board to be printed to hold them closely against the upright g'. It will be noticed that it has a lip extending down between the slotted springs to prevent the under board being drawn back by the bed upon 80 its return.

Mounted in the slideways of the frame and fitted to run easily therein is the bed-plate B. This is driven by the pitman P, which is attached to the bed at the under side by the lug B², and any form of attachment may be used. The pitman is driven by the ordinary crank motion, either by a band-wheel and crank-shaft on the frame of the machine, or from other source, as most convenient. Bolted on each side of the lug B² are the arms S' S', 85 90 95 100

which extend down and outward beyond the frame and carry the shoes S S. Fitted in the face of the bed-plate is an ink-disk *d*, Fig. 1, which is attached to a ratchet or similar device to make a partial revolution at each journey of the bed-plate, the same as the ordinary press, and on this disk the ink is spread, which is used in the process. Set in the face of the bed-plate is a small dog *e'*, the use of which will be explained further on. In front of this the bed-plate is cut down to form the type-bed *B'*, in which the form is set. The toe of the bed *B'* comes up nearly to the line of the face of the bed-plate to form a support for the type-form, and also serves to draw back the fingers *f f*, which drive the boards through the press.

Across the frame is an ink-roller *I*, set low enough that it reaches the type when they go under it, and also pressing the ink-disk when it passes back and forth. The roller is mounted in boxes having stems *i i*, which go down through the frame and through lugs on the outside of the frame. Near the lower end of the stem a pin is put through, and between this and the lug is a coiled spring to hold the roller down, except when it is raised by the shoe, as noted further on.

Seated and riveted in the inner sides of the gage-plates *G G* are the slotted springs *H H*, which need to be made of steel, and which are left free beyond the gage-plates, and are extended beyond the end of the frame. Mounted in the slots of these spring-plates are the fingers *f f*, of which a cross-section is shown in Fig. 3. These are deep enough below the springs, that they are driven forward by the face of the bed and are drawn back by the toe of it when it returns. The dog *e'* needs to project just as far forward of the plate as the length of these fingers, so that they are in line when they reach the board.

A heavy pressure-roller *R* is at the end of the frame, and is carried in adjustable boxes, as shown in Fig. 4, so that it may be raised or lowered, as a greater or less pressure upon the type is desired. A type of hardened steel may be used without ink, if desired, and the letters cut into the board.

The method of operation of the press can be readily understood, and is as follows: The type are set and the form adjusted so as to print between the spring-plates *H H*. The boards to be printed are piled in flat on these plates, and the gages and uprights are adjusted so as to hold them substantially close

but not tight. When the press is started and the bed moves forward, the shoes *S S*, as they pass under the stems of the ink-roller boxes, raise them up at the moment that the dog *e'* goes under the roller; but at all the rest of the stroke the roller is held down firmly by the springs on the stems *i i*, and the type are inked by the roller. This in turn is inked from the ink-disk, upon which the ink is spread. When the face of the bed-plate comes forward, so that it catches the fingers *f f*, which are withdrawn beyond the boards, these and the dog *e'*, as they are driven forward, catch the lower board of the pile and drive it forward on the spring-plates under the pressure-roller *R*. The roller bears the board down upon the type, the springs yielding sufficiently to admit of a good impression, and the board is carried out beyond the roller. The bed has then reached the limit of its stroke, and when it returns, the toe of the bed *B'* catches the fingers *f f* and takes them back to their starting-point. It will be noticed that the back end of these fingers is cut away substantially to the level of the springs, thus forming a wedge, which raises the under boards as they are drawn back under the pile. As they go out, the boards drop down on the springs, ready for the next stroke.

Having thus described my invention and the method of its construction and operation, what I claim as new, and desire to secure by Letters Patent, is—

1. In a board-printing press having a fixed frame and longitudinally-moving bed, the adjustable gages *G*, with uprights *g' g'*, in combination with flat slotted spring-plates *H*, adjustable with the gages, said spring-plates having fingers *f f* to catch the boards and drive them through under the pressure-roller, where they are borne down upon the type and then forced out of the press, all substantially as shown and described. 100

2. In a printing-press of the kind described, the bed-plate *B*, with its type-bed *B'*, ink-disk *d*, and an ink-roller *I*, in combination with the spring-plates *H H* to support the boards, said spring-plates having sliding fingers 105 driven by the bed-plate to catch the boards and carry them forward under the pressure-roller, where they are borne down upon the type and receive the impression, all substantially as shown and described.

GEORGE W. MCELHONE.
